CLAIM

The ornamental design for an earring, as shown and described.

DESCRIPTION

FIG. 1 is a perspective view of an earring showing our new design.

FIG. 2 is a front view of the earring of FIG. 1.

FIG. 3 is a back view of the earring of FIG. 1.

FIG. 4 is a left view of the earring of FIG. 1.

FIG. 5 is a right view of the earring of FIG. 1.

FIG. 6 is a top view of the earring of FIG. 1; and,

FIG. 7 is a bottom view of the earring of FIG. 1.

The broken lines shown in the drawings represent portions of the earring that form no part of the claimed design.

1 Claim, 5 Drawing Sheets
